UNITED STATES PATENT OFFICE

100,972

DESIGN FOR A FOOTBALL HELMET

Harry M. Pryale and Samuel C. Clark,
Pontiac, Mich.

Application December 2, 1935, Serial No. 59,880

Term of patent 3½ years

To all whom it may concern:

Be it known that we, Harry M. Pryale and Samuel C. Clark, citizens of the United States of America, residing at Pontiac, in the county of Oakland and State of Michigan, have invented a new, original, and ornamental Design for a Football Helmet, of which the following is a specification, reference being had therein to the accompanying drawing forming a part thereof, in which

Figure 1 is a front elevational view of the helmet showing the design;

Figure 2 is a side elevation;

Figure 3 is a rear elevation; and

Figure 4 is a top plan view thereof.

The dominant feature of our new design of football helmet consists in the downwardly extending ear protecting portions forming in appearance continuations of opposite sides of the crown and having ear receiving pockets provided with outer surfaces tapering inwardly from the rear of the pockets to the forward edges of the ear protecting portions.

We claim:

The ornamental design for a football helmet, substantially as shown and described.

HARRY M. PRYALE.
SAMUEL C. CLARK.
